(57) **CLAIM**

The ornamental design for an air conditioning apparatus, as shown and described.

DESCRIPTION

FIG. 1 is a perspective view of an air conditioning apparatus; FIG. 2 is a first side view of the air conditioning apparatus of FIG. 1;

FIG. 3 is a second side view of the air conditioning apparatus of FIG. 1;

FIG. 4 is a third side view of the air conditioning apparatus of FIG. 1;

FIG. 5 is a fourth side view of the air conditioning apparatus of FIG. 1; and,

FIG. 6 is a top view of the air conditioning apparatus of FIG. 1.

The broken lines in the drawings illustrate portions of the air conditioning apparatus which form no part of the claimed design.
